LEVELING INSTRUMENT

Thomas Midgley III, Los Angeles, and Robert E. Forrester, Camarillo, Calif., assignors to Forrgley, Inc., Los Angeles, Calif.

Filed July 22, 1974, Ser. No. 490,736

Term of patent 14 years

Int. Cl. D10—05

U.S. Cl. D10—65

FIG. 1.

FIG. 2.

FIG. 3.

FIG. 4.

FIG. 5.

FIG. 1 is a front perspective view of a leveling instrument showing our new design;

FIG. 2 is an enlarged left side elevational view of element thereof, the hose and other element having been omitted for ease of illustration;

FIG. 3 is a top view of FIG. 2 taken from perpendicular to the angled gauge surface;

FIG. 4 is a right side elevational view of FIG. 2; and

FIG. 5 is a rear elevational view of FIG. 2 as taken from the left.

We claim:

The ornamental design for a leveling instrument, as shown and described.
